ROAD DRAG

Filed Feb. 6, 1928

Inventor
P. M. Skinner,

By Clarence A. O'Brien
Attorney

UNITED STATES PATENT OFFICE.

PHILLIP M. SKINNER, OF DALLAS, TEXAS.

ROAD DRAG.

Application filed February 6, 1928. Serial No. 252,288.

The present invention relates to improvements in road drags and has for its principal object to provide a ground engaging unit that presents two surface engaging edges.

5 One of the important objects of the present invention is to provide a road drag which is simple in construction, inexpensive, strong and durable and further well adapted to the purpose for which it is designed.

10 Other objects and advantages of the invention will become apparent during the course of the following description when taken in connection with the accompanying drawing.

In the accompanying drawing wherein like 15 reference characters indicate corresponding parts throughout the several views:

Figure 1 is a top plan view of the road drag embodying my invention, showing two units secured together in parallel spaced relation,

20 and

Figure 2 is a side elevation thereof.

In the drawing wherein for the purpose of illustration is shown the preferred embodiment of my invention, the numeral 1 designates generally my improved road drag, the same comprising a pair of parallel spaced units 2 and 3, respectively. Each unit consists of an elongated metallic member that is curved transversely throughout its entire 25 length whereby to provide two ground engaging edges indicated at 4 with reference 30 and more particularly to Figure 2.

The units are secured together in properly spaced relation through the medium of the 35 transversely extending struts 5, the same extending through registering slots formed in the units and being welded or otherwise rigidly attached thereto.

The forward ends of the struts are bent to 40 provide loops 6 and as is clearly illustrated in Figure 1, one of such struts is arranged adjacent each end of the elongated units 2 and 3.

Suitable brace rods 7 extend between the struts 5 for further adding to the rigidity of 45 the drag.

A pair of forwardly converging draft rods 8 are formed at their rear ends with eyes 9 for interfitting engagement with the respec-

tive loops 6 of the struts 5, the converging forward ends of the rods being formed with 50 smaller eyes 10 to which are connected the rear ends of short lengths of chains 11, the chains being in turn connected to the ring 12 that is adapted to be connected in any appropriate manner to a draft appliance, not shown, 55 for facilitating the forward movement of the drag along the ground.

In the present instance, two ground engaging units are disclosed, and therefore four earth working edges are provided due to the 60 construction of each of the units and additional units may be added in order to increase the number of earth engaging blades as may be desired.

The top of each unit is formed with suitable 65 openings 13 for the purpose of facilitating the attachment of additional weights, not shown.

It is also to be understood that the units of the drag may vary in length. A road drag 70 constructed in accordance with the present invention will be very inexpensive and due to its simplicity will at all times be positive and efficient in carrying out the purposes for which it is designed.

While I have shown the preferred embodiment of my invention it is to be understood that minor changes may be made therein without departing from the spirit of the invention and the scope of the appended claim.

Having thus described the invention, what 80 I claim as new and desire to secure by Letters Patent is:—

In a road drag, a pair of metallic members, each of which is curved transversely throughout its entire length to provide a plurality of 85 ground engaging edges, transversely extending struts rigidly secured to the members for holding the same in parallel spaced relation, said members being formed with registering slots through which the respective struts extend, and means secured to the forward ends 90 of the struts to afford a connection of the drag with a draft appliance.

In testimony whereof I affix my signature.

PHILLIP M. SKINNER.
